CORE BOX

John W. Lowther, Pittsburgh, Pa., assignor to
 Kerotest Manufacturing Company, Pittsburgh,
 Pa., a corporation of Pennsylvania

Application March 31, 1944, Serial No. 528,877

7 Claims. (Cl. 22—13)

My invention relates to core-boxes, particularly to core-boxes for making cores used in the casting of globe valves.

The invention consists in certain new and useful improvements in core-box structure, whereby the production of cores may be accomplished more expeditiously and with greater accuracy.

The invention will be understood upon reference to the accompanying drawings, in which:

Figure 1 is a view in vertical or axial section of a globe valve of the conical seat type, the type in whose production a core formed in the core-box of this invention may be used;

Figure 2 is a view in side elevation of a core made in a core-box of the invention;

Figure 3 is a bottom view of the two component parts that are united to form the core;

Figure 4 is a view in end elevation of the core;

Figure 5 is a view in plan of one of the two complementary parts of a core-box which in exemplary way embodies the invention;

Figure 6 is a view of the core-box part in section, on the plane VI—VI, Figure 5;

Figures 7 and 8 are views in elevation, one view shown at right angles to the other, of a certain molding element of the core-box structure; and

Figures 9 and 10 are two views similar to Figures 7 and 8 of a certain guideway that cooperates with the molding element.

Referring to the drawings, the globe-valve structure comprises a housing or casing 2 of cast steel or other suitable metal. The casing is of spheroidal or ovate form, and is provided with the usual flanges 5 and 6 that are engaged by complementary flanges carried by the pipe line or duct in which the globe-valve is incorporated. Internally, the casing 2 includes a partition having a horizontal seat portion 7 that is ported, as at 8. The port 8 is circular as viewed in plan, and the rim of the port is machined, or a machined insert is provided, to receive a valve element (not shown). The valve element is movable relatively to the seat to open and close the port 8 and thereby control the flow of fluid in the pipe line.

The complete globe-valve structure includes a bonnet that is secured to the usual flange 9, and the operating stem of the valve extends through the bonnet and carries the valve element. None of these latter parts of the conventional globe-valve structure is illustrated herein. They are known items of valve construction and have no immediate bearing on the present invention. Suffice it to note that internal partition of the

valve casing includes a horizontal, ported seat portion 7 that is integrated to the spheroidal side walls of the valve casing 2, by means of conically shaped webs or division wall portions 10 and 11.

The web portion 10 consists in a segment of an upwardly diverging conical shell which, located above the seat portion 7, extends from a point 12 of tangency with one side wall of the casing, through 180° about the vertical axis of the port 8, to a point of tangency with the side wall of the casing that is located opposite to the point 12. In similar manner the web portion 11 consists in the segment of a downwardly diverging conical shell that, located below the seat portion 7, extends from the point 12 through 180° on said axis, and together with the web portion 10 and the seat portion 7 completes the integral division wall or partition which, save for the port 8, entirely closes or blanks the inlet I, of the valve structure from the outlet O. It will be understood that the valve casing with its flanges, and the partition 7, 10, 11 comprise a unitary metal casting, the lines 10a and 10b, indicating the manner in which the web 10 merges with each side wall of the valve casing, and the lines 11a and 11b affording a similar indication with respect to the web 11.

It will be understood that the external shape of the valve casing is determined by the matrix of the mold (not shown) in which the metal is cast, while the internal form of the casing is determined by a core, such as the core 3 illustrated in Figures 2 and 4. The core is secured in the matrix of the mold, and the space formed by and between the surfaces of the matrix and the core body is identical in shape with the integral valve casing and its ported partition. The body of the core 3 includes cylindrical hubs a, b, and c, and the portions of such hubs which extend outwardly from the dotted lines L form no part of the metal-shaping matrix of the mold and core assembly, but provide the support for the core in place within the mold, it being understood that the mold is provided with cylindrical cavities that extend outwardly from the mold matrix to receive said support-affording portions of the core.

The body of the core includes recesses 10c and 11c which are accurately shaped to form the seat and web portions 7, 10 and 11 in the cast body of the valve casing 2, while a central portion 8c in the core body forms the port 8.

In practice, the core 3 is molded in two halves 3a and 3b, as shown in Figure 3, of any suitable core-forming material. The half 3b is molded in

the core-box member 13 shown in Figures 5 and 6, and the half 3a is molded in a core-box member (not shown) which is the counterpart of the core-box member 13. When a core half has been molded in a core-box member, the molded article is removed and baked, and, in the baking, rigidity and integrity are imparted to the molded material. Two core halves, 3a and 3b, when so molded and integrated are assembled face to face and cemented or bonded together to provide a complete core 3, as shown in Figures 2 and 4. This practice is well known to the art, and the invention will be clearly and fully understood from the illustration and description of one of the core-box members 13, it being realized that the counterpart of such core-box member is utilized in the same general way, and embodies the same features of invention. For simplicity of expression in the ensuing specification and claims, the core-box member 13 will be termed a core-box.

Referring to Figures 5 and 6, the core box 13 includes a matrix 14, having a semi-spheroidal central portion 15 to shape the core material molded therein to the configuration of the internal surface of one side wall of the valve casing 2. Extending outward from the central matrix portion 15 are semi-cylindrical cavities 16, 17 and 18, to form the portions *a*, *b* and *c* of the core half molded therein. The core-box 13 may be constructed in the main of wood, but around the periphery of the matrix a border 19 formed plate metal is provided, the upper surface of this metallic border lying in the plane that defines the flat face of the core half which is fashioned in the core-box. The metallic border 19 provides a planar bearing for the usual straight-edged tool that is used to level-off the core material molded in box.

Coming now to the features in which the invention is particularly centered, it will be noted that two curved molding elements 20 and 21 extend into the mold matrix. The molding element 20 forms in the core half molded in the box one half of the recess 10c of the completed core, while the element 21 forms one half of the recess 11c, and together the two elements provide a semi-cylindrical mold portion that forms one half of the cylindrical portion 8c of the completed core which in the ultimate metal-casting operation forms the port 8 in the valve seat 7; see Figure 1. Remembering that the core 3 is formed of two halves, one half produced in the core-box 13 and the other half produced in a complementary core-box that is not illustrated, the functions of the molding elements 20 and 21 may at this point be better explained as they are related to the production of the completed core shown in Figures 2 and 4.

Each of the molding elements 20 and 21 (and there are two of such molding elements in each of the two complementary core-boxes) includes a portion *e* that forms within the completed core 3 one-quarter of the recess that shapes the cast metal into the seat 7 of the valve casing. The portion *e* is provided with an edge *d* that shapes one-quarter of the cylindrical portion 8c of the core that forms the port 8 in the valve seat. Continuing outward from the portion *e*, each molding element includes a web portion *f* that forms one-half of the recess portion in the core that shapes the cast metal into one of the conical web or shell segments (10 or 11) that integrate the valve seat 7 to the valve casing. That is to say, the portion *f* of the molding element 20 pro-

vides in the core one-half of the recess that shapes the metal into the upper conical web segment 10, while the portion *f* of the molding element 21 provides in the core body one-half of the recess 11, and it will be understood that each of the two core-box members (only one of which is herein illustrated) includes two molding elements 20 and 21. The elements 20 and 21 in one core-box member are the counterparts of the similar elements in the other core-box member. Having this description of the function of the molding elements in mind, attention will now be given to the features of their construction.

Each molding element 20, 21 is carried by or equipped with a curved guide portion 22 having a handle 23. It will be perceived that the molding element is rigidly secured to and spaced from the guide portion 22 by means of a connecting arm 24, and it will be noted that the body of the core-box is countersunk in its face to receive arm 24 in such manner that the outer face of the arm lies flush with the surface of the plate metal border 19.

The guide portion 22 of each molding element is shaped to the circular curvature of the portions *e* and *f*, and is provided with a longitudinally extending beveled rib 22a that is slideably engaged in a beveled groove 25 in a curved guideway member 26. The core-box is formed with a chamber 27 having a wall 28 that extends in a plane parallel to the plane of the portions *e* of the molding elements that shape the valve-seat-forming recess in the core, and upon this wall the guideway member 26 is rigidly secured (say by screw nuts) in position of concentricity with respect to the common center of curvature of the portions *e* and *f* of the molding element. The guide 22, by virtue of the engagement of its beveled rib 24 with the beveled groove of the member 26, is movable in the direction of curvature of the supported molding element, whereby the molding element may be removed from the body of core material that is shaped, tamped and leveled off in the matrix of the core-box. This is a feature of great importance. The structure is such that, when a core half has been molded in the box, the molding element may be cleanly withdrawn from the molded core material, withdrawn without dislodging portions of the molded material, as hitherto has been the case and has required the patching of the molded core. The engagement of the guide portion 22 with the guideway 26 insures that the molding element, by lifting on the handle 23, may be removed in precisely the direction that will permit clean and free withdrawal from the molded but crumbly material. It is important to note that the guide portion 22 is of greater arcuate extent than the arc through which the molding element is moved, so that the molding element is supported until after it has been entirely removed from the molded material. The dotted lines in Figure 6 illustrates the molding element 20 in the course of its removal from the matrix of the core-box, but it will be noted that the core-box will be positioned face upward, as it is shown in Figure 5, when the molding element is removed. The core-box is inverted, as it is shown in Figure 6, only after both molding elements 20 and 21 have been removed, and the molded core half is to be deposited on a platen placed against the face of the box.

The molding element 21 is of the same general structure and is mounted in the same general manner as the element 20, but as is manifest in

Figures 5 and 6 the element 21 is arranged in opposing relation to the element 20, and the chamber 27a, in which the guideway and guide portions of element 21 are organized, is provided in the core-box body on the opposite side of the matrix from the chamber 27.

Whereas the core-box is in the main constructed of wood, the molding elements 29 and 21 and their associate parts 22, 25 and 26 may be, and advantageously are, constructed of metal, 10 preferably aluminum.

By virtue of the structure described, the molding elements are not only removable from the molded core material in exactly the proper path to avoid impairment of the work, but they are rigidly supported in position of service in the mold. The engagement of the guide portions 22 with the guideways 26 is a snug sliding engagement that is preventative of any looseness of the supported molding elements. Additionally, the arms 24 snugly fit in recesses provided therefor in the core-box body; the edges *h* of the web portions *f* of the molding elements snugly engage the slots in the matrix wall through which they extend; and the meeting ends of the two molding elements are overlapped and interengaged in a joint *i*. All of these features make for absolute security and rigidity of the molding elements, as is desired when core material is tamped into place within the matrix of the core-box. From the point *i* of interengagement of the two molding elements, each molding element extends through an arc of 90°, while as already described the guide portions 22 extend through an arc that is of greater effective length.

The core half molded in the box is deposited upon a metal platen, and on such platen it is supported in an oven wherein it is baked and solidified, ready to be united with a similarly prepared complementary core half.

Within the terms of the appended claims various modifications may be utilized, without departing from the spirit of the invention herein disclosed.

I claim as my invention:

1. A core-box for producing one of two complementary core halves that, joined together, are used in casting a globe-valve casing that has a valve seat with a port therein, said core-box including a matrix, two curved molding elements extending into said matrix to form in the core half molded therein a recess and a core body portion for shaping cast metal to the form of said ported valve seat, a curved guideway in the core-box structure for each molding element, each molding element being provided with a curved guide portion for engagement with a guideway to support the molding element in proper position in said matrix, the guide portion of each molding element being movable longitudinally of the engaged guideway to move the supported molding element on the line of its curvature from said matrix.

2. A core-box for producing one of two complementary core halves that, joined together, are used in casting a globe-valve casing that has a valve seat with a port therein, said core-box including a matrix, two curved molding elements extending into said matrix to form in the core half molded therein a recess and a core body portion for shaping cast metal to the form of said ported valve seat, said molding elements meeting in overlapped engagement and extending from the point of engagement each through an arc of substantially 90°, a curved guideway

in the core-box structure for each molding element, each molding element being provided with a curved guide portion for engagement with a guideway to support the molding element in proper position in said matrix, the guide portion of each molding element being movable longitudinally of the engaged guideway to move the supported molding element on the line of its curvature from said matrix.

3. A core-box for producing one of two complementary core halves that, joined together, are used in casting a globe-valve casing that has a valve seat with a port therein, said core-box including a matrix, two curved molding elements extending into said matrix to form in the core half molded therein a recess and a core body portion for shaping cast metal to the form of said ported valve seat, a curved guideway in the core-box structure for each molding element, each molding element being provided with a curved guide portion for engagement with a guideway to support the molding element in proper position in said matrix, the guide portion of each molding element being movable longitudinally of the engaged guideway to move the supported molding element on the line of its curvature from said matrix, the effective arcuate extent of the engagement of each guide portion with its guideway being greater than the arcuate extent of the corresponding molding element, whereby the molding element in its movement is positively guided until it is completely removed from said matrix.

4. A core-box for producing one of two complementary core halves that, joined together, are used in casting a globe-valve casing that has a division wall between the valve inlet and outlet, the division wall comprising a ported seat portion integrated to the wall of the valve casing by two frusto-conical webs each of substantially 180° extent peripherally of the seat, with one web located on one side of the seat and the other web on the opposite side; said core-box including a matrix, two curved molding elements extending into said matrix to form in the core half molded therein a recess and a core body portion for shaping cast metal to the form of said division wall, a curved guideway in the core-box structure for each molding element, each molding element being provided with a curved guide portion for engagement with a guideway to support the molding element in proper position in said matrix, the guide portion of each molding element being movable longitudinally of the engaged guideway to move the molding element on the line of its curvature from said matrix.

5. A core-box or mold including a matrix, two molding elements each in the form of a segment of a conical shell, an arcuate guide secured to each of said molding elements, and two guideways arranged in the core-box structure severally to receive said guides, with the molding elements supported in said matrix and with the cone axes of the molding elements arranged in alignment but with the divergence of the conical body of one molding element extending in opposite direction from that of the other, said guides being severally movable along said guideways in curved paths that are concentric with the aligned cone axes to remove the molding elements from said matrix.

6. A core-box or mold including a matrix, a molding element in the form of a segment of a shell of circular transverse section, an arcuate guide axially spaced from but concentric with

the axis of revolution of the shell, means for rigidly securing said arcuate guide to said shell, and a guide-way in the core-box to receive said guide, with the molding element supported in said matrix, said guide being movable along said guide-way in a curved path that is concentric with said axis to remove the molding element from the matrix.

7. A core-box or mold including a matrix, two molding elements each in the form of a segment of a conical shell, an arcuate guide for each molding element, means for securing each guide to its conical molding element in a position spaced

therefrom but concentric with the axis of the conical body thereof, and two guideways arranged in the core-box structure severally to receive said guides, with the molding elements supported in said matrix and with the cone axes of the molding elements arranged in alignment but with the divergence of the conical body of one molding element extending in opposite direction from that of the other, said guides being severally movable along said guide-ways in curved paths that are concentric with the aligned cone axes to remove the molding elements from said matrix.

JOHN W. LOWTHER.
